PROCESS FOR MANUFACTURING
BUTYRALDEHYDE

Louis Alhéritière, Beau-Soleil, Melle, France, assignor to Les Usines de Melle (Societe Anonyme), Saint-Léger-les-Melle, France, a corporation of France

1

This invention relates to the manufacture of butyraldehyde by hydrogenation of crotonaldehyde.

Hydrogenation of crotonaldehyde to produce butyraldehyde is known. However, despite the care taken in conducting such operation, it has been impossible, until now, to limit the reaction to the hydrogenation of the ethylenic bond only and to avoid to a great extent the hydrogenation of the aldehydic group. As a matter of fact, the known processes always permit large quantities of butyl alcohol to be formed beside the butyraldehyde, which is the desired product.

The principal object of the present invention is to provide an improved process for producing very high yields of butyraldehyde.

The invention accordingly comprises the novel processes and steps of processes, specific embodiments of which are described hereinafter by way of example and in accordance with which I now prefer to practice the invention.

The process of the present invention, in which crotonaldehyde is hydrogenated at high temperature in the presence of a catalyst capable of hydrogenating crotonaldehyde into butyl alcohol and butyraldehyde, comprises passing over the catalyst, crotonaldehyde in admixture with butyl alcohol, the butyl alcohol being afterwards recovered and, if the operation is conducted continuously, returned to the reaction zone together with further crotonaldehyde. The catalyst is preferably a copper catalyst, such as copper deposited on a carrier or copper-chromium catalyst.

For 1 molecule of crotonaldehyde, there are supplied to the reaction apparatus 1 to 5 molecules, and preferably 2 to 3 molecules, of butyl alcohol, together with 1 to 2 molecules of hydrogen. The hydrogen, for example, may result from the dehydrogenation of ethyl alcohol.

According to a preferred embodiment of this invention, a mixture of crotonaldehyde, butyl alcohol and hydrogen is passed over a copper catalyst maintained at about 150-220° C. and preferably at 150-200° C. In this way, more than 95% of the crotonaldehyde employed can be transformed; the amount of butyl alcohol that is formed is very small and, when the operation is effected under the best conditions, may even be almost zero (less than 1%). On the other hand, 6 to 9% of products having higher boiling points, are obtained; these products consist mainly of butyl butyrate.

With a view to simplifying the various operations, one may utilize crotonaldehyde satu-

rated with water, for example, the crotonaldehyde which forms the upper layer by the decantation of the azeotropic mixture of water and crotonaldehyde, obtained by distillation of the raw product of the "crotonization" of acetaldol, as set forth in applicant's copending application Serial No. 727,491, filed February 10, 1947, now Patent No. 2,489,608, for example.

The raw product of the hydrogenation of the crotonaldehyde prepared in accordance with the present invention is fractionated by distillation: From the head of a first column one withdraws, on the one hand, aqueous butyraldehyde containing 95-96% of butyraldehyde, and on the other hand, water containing small quantities of butyraldehyde which are recovered by distillation in an exhausting column. At the foot of the first column, an anhydrous mixture of butyl alcohol, unconverted crotonaldehyde and products having higher boiling points, is collected and sent into a second column from the head of which anhydrous butyl alcohol and unconverted crotonaldehyde are withdrawn, and at the foot of which are collected the higher products (higher boiling products), which may contain or not contain small quantities of butyl alcohol, according to the conditions of distillation. The anhydrous butyl alcohol and unconverted crotonaldehyde are returned to the hydrogenation apparatus. The mixture of higher products and (eventually) butyl alcohol may be separated into its elements by distillation.

Of course, if the hydrogenation apparatus is supplied with anhydrous crotonaldehyde instead of aqueous crotonaldehyde, anhydrous butyraldehyde is obtained at the head of the first column, instead of aqueous butyraldehyde.

The following Examples 1 and 2 represent the process in accordance with the present invention as I now prefer to practice it. It is to be understood that these examples are illustrative and the invention is not to be considered as limited thereto except as indicated in the appended claims. In Examples A and B below, processes are given for purposes of comparison which are not in accordance with the present invention, in order to emphasize the advantages realized in the practice of the invention.

EXAMPLE 1

A copper catalyst is prepared by reacting in the heat, sodium hydroxide with an aqueous solution of copper nitrate, containing kieselguhr in suspension therein. The copper hydroxide precipitates on the kieselguhr which is after-

wards filtered off and washed. The kieselguhr-copper hydroxide mass is pelleted and reacted with hydrogen to reduce the copper hydroxide to metallic copper. This reduction is effected in the hydrogenation furnace in which the crotonaldehyde is to be hydrogenated.

Into the hydrogenation furnace, containing 120 liters of copper catalyst pellets obtained as above, and which is maintained at a temperature of 165° C., one introduces continuously per hour:

45 liters of crotonaldehyde saturated with water, i. e., 35 kgs. of pure crotonaldehyde;

92 liters of anhydrous butyl alcohol recovered from a previous operation and containing about 74 kgs. of butyl alcohol and 0.7 kg. of crotonaldehyde, and

17 cubic meters of hydrogen.

Thus, the actual crotonaldehyde feed is 35.7 kgs. per hour.

The mixture of gases and vapors flowing out of the hydrogenation furnace is submitted to condensation by cooling, then to scrubbing for recovering the valuable products which have not been condensed. It is to be noted that the scrubbing may be omitted if the condensation operation is efficient enough.

The residual gases consist of 4 to 5 cubic meters per hour of hydrogen, containing a little CO₂ and hydrocarbons.

The products of the reaction are separated from one another by distillation as above described.

From the head of the first column, one draws off per hour 34.2 kgs. of butyraldehyde saturated with water, containing 95.6% butyraldehyde by weight, i. e., 32.6 kgs. of pure butyraldehyde.

From the head of the second column, one draws off per hour an anhydrous mixture of 74 kgs. of butyl alcohol and 0.7 kg. of crotonaldehyde, which mixture is returned to the hydrogenation furnace with further crotonaldehyde.

At the foot of the second column, one collects per hour a mixture of 0.33 kg. of anhydrous butyl alcohol and 2.6 kgs. of products boiling from 130 to 220° C.

Of the 35.7 kgs. of crotonaldehyde fed into the hydrogenation furnace, 35 kgs. have been transformed; the transformation ratio is:

$$\frac{35 \times 100}{35.7} = 98\%$$

The balance sheet of the operation is as follows:

	Yield, percent
32.6 kgs. of pure butyraldehyde corresponding to 31.7 kgs. of crotonaldehyde	90.9
0.33 kg. of anhydrous butyl alcohol corresponding to 0.315 kg. of crotonaldehyde	0.9
2.6 kgs. of higher boiling products corresponding to 2.49 kgs. of crotonaldehyde	7.1
Total yield	98.9

No decrease of the activity of the catalyst has been observed after 1000 hours of working.

I describe below an operation which is conducted in the same apparatus and exactly under the same conditions as above, but without introducing butyl alcohol into the hydrogenation furnace:

Example A.—Into the hydrogenation furnace, containing 120 liters of copper catalyst pellets

as above and maintained at 165° C., one introduces per hour:

46 liters of crotonaldehyde saturated with water, i. e., 35.7 kgs. of pure crotonaldehyde, and

17 cubic meters of hydrogen.

The reaction products are submitted to the separation as above described under Example 1, and the results of the distillation are as follows:

From the head of the first column, one draws off per hour 20.8 kgs. of aqueous butyraldehyde containing 95.6% butyraldehyde by weight, i. e., 19.9 kgs. of pure butyraldehyde.

From the head of the second column, one draws off per hour 6.8 kgs. of unconverted crotonaldehyde.

At the foot of the second column, one collects per hour 9.4 kgs. of a mixture containing 2.2 kgs. of butyl alcohol and 7.2 kgs. of higher products.

Of the 35.7 kgs. of crotonaldehyde fed into the hydrogenation furnace, 28.9 kgs. have been transformed; the transformation ratio is:

$$\frac{28.9 \times 100}{35.7} = 81\%$$

The balance sheet of the operation is as follows:

	Yield, percent
19.9 kgs. of pure butyraldehyde corresponding to 19.4 kgs. of crotonaldehyde	87.0
2.2 kgs. of anhydrous butyl alcohol corresponding to 2.08 kgs. of crotonaldehyde	7.2
7.2 kgs. of higher boiling products corresponding to 7.0 kgs. of crotonaldehyde	24.2
Total yield	98.4

This demonstrates that working in the absence of previously-introduced butyl alcohol leads to a considerable decrease of the yield in butyraldehyde, which is the desired product, the yields in undesirable butyl alcohol and higher-boiling products being correspondingly increased. However, the conditions of working that have just been described are far from being the most favorable for obtaining the best yield in butyraldehyde. When one is working in the absence of previously-introduced butyl alcohol, one must, for the best results, increase the temperature in the furnace and the rate of feed of crotonaldehyde, and decrease the rate of feed of hydrogen. However, I have found that, even under these conditions, the results that are obtained are still far below those obtained when working in the presence of previously-introduced butyl alcohol according to the present invention; such a comparative experiment is illustrated as follows:

Example B.—Into the hydrogenation furnace, containing 120 liters of copper catalyst pellets as above and maintained at 180° C., one introduces per hour:

100 liters of crotonaldehyde saturated with water, i. e., 78 kgs. of pure crotonaldehyde, and 32 cubic meters of hydrogen.

After condensation and scrubbing of the reaction products, 6 to 7 cubic meters of pure hydrogen are recovered per hour.

The reaction products are submitted to distillation as above, the results of which are as follows:

From the head of the first column, one draws off per hour 57.5 kgs. of butyraldehyde saturated with water, containing 95.6% butyraldehyde by weight, i. e., 55 kgs. of pure butyraldehyde.

From the head of the second column, one draws off per hour 9 kgs. of unconverted crotonaldehyde, which one returns to the hydrogena-

tion furnace in admixture with fresh crotonaldehyde.

At the foot of the second column, one collects per hour 15.45 kgs. of a mixture containing 4.85 kgs. of anhydrous butyl alcohol and 10.6 kgs. of products boiling from 130 to 220° C.

Of the 78 kgs. of crotonaldehyde fed into the hydrogenation furnace, 69 kgs. have been transformed; the transformation ratio is:

$$\frac{69 \times 100}{78} = 88.4\%$$

The balance sheet of the operation is as follows:

	Yield, percent	15
55 kgs. of pure butyraldehyde corresponding to 53.3 kgs. of crotonaldehyde	77.2	
4.85 kgs. of anhydrous butyl alcohol corresponding to 4.6 kgs. of crotonaldehyde	6.7	
10.6 kgs. of higher boiling products corresponding to 10.2 kgs. of crotonaldehyde	14.8	
Total yield	98.7	20

The length of life of the catalyst in both Examples A and B is considerably smaller than its length of life when working in the presence of previously-introduced butyl alcohol: After 180 hours of working in the conditions just described in Example B, one ascertains a sudden fall of the transformation ratio down below 60%. A similar decrease occurs with Example A.

The advantage of the process of the invention is then evident, since this process provides:

A transformation ratio of 98% as against 88%; A yield in butyraldehyde of 90.9% as against 77.2%;

A yield in butyl alcohol of only 0.9% as against 6.7%, and since it permits, on the other hand, of increasing ten times or more the life of the catalyst.

EXAMPLE 2

The copper catalyst that is used is a copper-chromium catalyst prepared by reacting in the heat, sodium hydroxide with an aqueous solution of copper nitrate and chromium chloride (the weight of chromium being 5% with respect to the weight of copper), containing kieselguhr in suspension therein. The copper and chromium hydroxides precipitate on the kieselguhr which is afterwards treated as described in Example 1 above.

Into the hydrogenation furnace, containing 120 liters of copper-chromium catalyst pellets obtained as has just been described, and which is maintained at a temperature of 160° C, one introduces continuously per hour:

50 liters of crotonaldehyde saturated with water, i. e., 39 kgs. of pure crotonaldehyde;

90 liters of anhydrous butyl alcohol recovered from a previous operation and containing 72 kgs. of butyl alcohol and 1 kg. of crotonaldehyde, and 18 cubic meters of hydrogen.

Thus, the actual crotonaldehyde feed is 40 kgs. per hour.

The mixture of gases and vapors flowing out of the hydrogenation furnace is submitted to condensation by cooling, then to scrubbing as in Example 1.

The residual gases amount to about 4 cubic meters per hour.

The products of the reaction are separated from one another by distillation as above described.

From the head of the first column, one draws off per hour 38.5 kgs. of butyraldehyde saturated

with water, containing 95.6% butyraldehyde by weight, i. e., 36.8 kgs. of pure butyraldehyde.

From the head of the second column, one draws off per hour an anhydrous mixture of 72 kgs. of butyl alcohol and 1 kg. of crotonaldehyde, which mixture is returned to the hydrogenation furnace with further crotonaldehyde.

At the foot of the second column, one collects per hour a mixture of about 0.5 kg. of anhydrous butyl alcohol and about 3 kgs. of products boiling from 130 to 220° C.

Of the 40 kgs. of crotonaldehyde fed into the hydrogenation furnace, 39 kgs. have been transformed; the transformation ratio is:

$$\frac{39 \times 100}{40} = 97.5\%$$

The balance sheet of the operation is as follows:

	Yield, percent	25
36.8 kgs. of pure butyraldehyde corresponding to 35.3 kgs. of crotonaldehyde	90.3	
0.5 kg. of anhydrous butyl alcohol corresponding to 0.47 kg. of crotonaldehyde	1.2	
3 kgs. of higher boiling products corresponding to 2.88 kgs. of crotonaldehyde	7.4	
Total yield	98.9	

What I claim is:

1. A process which comprises heating a mixture of crotonaldehyde, butyl alcohol and hydrogen at a temperature above the boiling point of the mixture thereof in the presence of a copper base catalyst, said butyl alcohol being present in the proportion of at least 1 mole of butyl alcohol to 1 mole of crotonaldehyde and converting the crotonaldehyde into butyraldehyde.
2. A process which comprises passing a mixture of crotonaldehyde, butyl alcohol and hydrogen over a heated copper base catalyst at a temperature above the boiling point of the mixture thereof, said butyl alcohol being present in the proportion of at least 1 mole of butyl alcohol to 1 mole of crotonaldehyde, converting the crotonaldehyde substantially completely into butyraldehyde, and separating the butyraldehyde from the butyl alcohol after passage of the mixture over the catalyst.
3. A process which comprises continuously passing a mixture of crotonaldehyde, butyl alcohol and hydrogen over a copper base catalyst at a temperature above the boiling point of the mixture thereof, said butyl alcohol being present in the proportion of at least 1 mole of butyl alcohol to 1 mole of crotonaldehyde continuously recovering butyraldehyde and butyl alcohol from the resulting mixture, continuously returning the butyl alcohol for mixture with a further amount of crotonaldehyde and hydrogen and continuously passing such mixture over the catalyst.

4. A process in accordance with claim 3, in which the mixture of crotonaldehyde, butyl alcohol and hydrogen contains 1 to 5 molecules of butyl alcohol to 1 molecule of crotonaldehyde.
5. A process which comprises continuously passing a mixture of crotonaldehyde, butyl alcohol and hydrogen at a temperature of about 150° C. to 220° C. over a copper base catalyst capable of hydrogenating crotonaldehyde to form butyraldehyde and butyl alcohol, said butyl alcohol being present in the proportion of at least 1 mole of butyl alcohol to 1 mole of crotonaldehyde continuously recovering butyraldehyde and butyl alcohol from the resulting mixture, continuously returning the butyl alcohol for mixture with a further amount of crotonaldehyde

and hydrogen, and continuously passing such mixture over the catalyst.

6. A process which comprises continuously passing a mixture of crotonaldehyde, butyl alcohol and hydrogen at a temperature of about 150° C. to 200° C. over a copper base catalyst capable of hydrogenating crotonaldehyde to form butyraldehyde and butyl alcohol, said mixture containing 2 to 3 molecules of butyl alcohol to 1 molecule of crotonaldehyde treated, continuously recovering butyraldehyde and butyl alcohol from the resulting mixture, continuously returning the butyl alcohol for mixture with a further amount of crotonaldehyde and hydrogen, and continuously passing such mixture over the catalyst.

7. A process in accordance with claim 3, in which the catalyst consists of metallic copper.

8. A process in accordance with claim 3, in which the catalyst is a metallic copper-chromium catalyst.

9. A process in accordance with claim 3, in which crotonaldehyde saturated with water is employed.
